(57) **CLAIM**

The ornamental design for the clip for connection to a stab terminal of an electrical buss, as shown and described.

DESCRIPTION

FIG. 1 is a perspective top view of the clip for connection to a stab terminal of an electrical buss, in accordance with our new design;

FIG. 2 is a top view of the clip for connection to a stab terminal of an electrical buss, in accordance with our new design;

FIG. 3 is a front view of the clip for connection to a stab terminal of an electrical buss, in accordance with our new design;

FIG. 4 is a left side view of the clip for connection to a stab terminal of an electrical buss, in accordance with our new design;

FIG. 5 is a right side view of the clip for connection to a stab terminal of an electrical buss, in accordance with our new design; and,

FIG. 6 is a bottom view of the clip for connection to a stab terminal of an electrical buss, in accordance with our new design.

The broken lines are included for the purpose of illustrating environment and form no part of the claimed design.
